UNITED STATES PATENT OFFICE.

SIDNEY C. WILSON, OF ROCHESTER, NEW YORK, ASSIGNOR TO WILSON PROCESS, INC.,
OF NEW YORK, N. Y., A CORPORATION OF NEW YORK.

INSEAM-BEATING MACHINE.

Application filed April 19, 1922. Serial No. 555,624.

To all whom it may concern:

Be it known that I, SIDNEY C. WILSON, a citizen of the United States, and resident of Rochester, in the county of Monroe and 5 State of New York, have invented an Improvement in Inseam-Beating Machines, of which the following description, in connection with the accompanying drawings, is a specification, like letters on the drawings 10 representing like parts.

My present invention relates to machines adapted for use in the manufacture of boots and shoes, and more particularly to a machine for beating and smoothing the inseam 15 of boots and shoes after the insoles are incorporated in the boot or shoe.

In the manufacture of boots and shoes, the attaching of the upper to the outer face of the insole, either by sewing or other fastening means, throws up a ridge or rib that 20 is of such height as to prevent proper fitting of the outsole to the shoe structure. To compensate for the height of the ridge or rib, it has been heretofore necessary to provide filling for the depression between the 25 ridges on either side of the insole. This is objectionable however, as it entails another operation to the already great number necessary.

30 In my development of the boot and shoe making art, I have devised an improved process of manufacture whereby a boot or shoe may be produced and in which the heretofore necessary ridge or rib of stitching or 35 inseam has been eliminated. Further, in such improved process I combine the good qualities of a Goodyear type of boot or shoe, as regards flexibility of sole, with the good qualities of a McKay type of shoe, 40 as regards strength and rigidity of structure. This improved process is fully explained in my copending application Serial No. 326,567, filed September 26, 1919, and the machine forming the subject matter of my present invention is adapted to be used as auxiliary 45 to and in conjunction therewith.

In my improved process, as disclosed in the copending application Serial No. 326, 567, and above referred to, I provide an insole having a channel cut on each face of the insole, the channel flap of the channel on the outer face of the insole being the flap to which the upper material is secured when lasted. In this lasting process, as practised

according to my improved process set forth 55 and claimed in the copending application above referred to, I may attach the upper to the channel flap by a row of stitching, separated groups of stitching or suitable securing means of any description. After 60 the lasting operation, there is present a pronounced ridge or rib extending along each side and the toe portion of the insole, and in a McKay type of shoe, it is not desirable that the space defined by the ridges be built 65 up with filler. No suitable beating machine for beating and smoothing this inseam has been devised prior to the present machine, and in practising the process set forth and claimed in the copending application above 70 referred to and wherein a McKay type of shoe is lasted by the Goodyear process, the beating down and smoothing out of this inseam becomes important.

My invention is not limited in its scope 75 to use in connection with my improved process as set forth in the copending application above referred to, and it may be used to great advantage in the manufacture of ordinary McKay type shoes.

The object of my invention therefore, is an improved inseam beating and smoothing machine for use in the manufacture of boots and shoes of the so-called McKay type.

In the accompanying drawing illustrating 85 the preferred embodiment of my invention, Fig. 1 is a front elevation; Fig. 2 is a side elevation; Fig. 3 is a plan view, and Fig. 4 is an end elevation of the beating and smoothing roller.

90 Referring to the drawing, 10 designates a standard on which is secured, by bolts 11, a base 12. At one end of this base 12 is secured an upright 13 by bolts 14, while at the front end of the base is secured, by bolts 15 a pair of spaced, upwardly and forwardly extending curved horns 17 and 18, on the side of one of which, as 18, is formed a bearing 19 that is in alinement with a bearing 20 at the top of the upright 13, these horns 100 being joined by a member 16. Rotatably mounted in the bearings 19 and 20 is a shaft 21 having mounted thereon, adjacent the bearing 20, tight and loose pulleys 22 and 23 respectively, while at the front end 105 is secured a bevel gear 24. Secured to the base 12 is a lug 25, to which is pivotally mounted the lower end of a belt shifting

lever 26, provided at its upper end with an operating handle 27 and with a belt engaging fork 28.

At the upper and forward ends of the curved horns 17 and 18 are formed bearings 29 and 30 respectively, and in which are rotatably mounted a shaft 31 provided at one end with a bevel gear 32 that meshes with and is driven by the bevel gear 24 on the main driving shaft 21. On this shaft 31, and located between the horns 17 and 18, is keyed a corrugated beating and smoothing roll 33, the corrugations of which are rounded as shown, and of any suitable size and number.

Slidably mounted on the base 12 between the horns 17 and 18 and under the plate 16, is a plate 34 and provided in the plate 16 is a slot 35 through which passes a bolt 36 that passes through the plate 34 and screws into the base 12, and by means of which the plate 34 may be adjustably held in position. On the outer, or forward end of the plate 34 is secured, by bolt 37, a conical beating and smoothing anvil 38, this construction being such that different sized anvils 38 may be used, corresponding to the sizes of boots and shoes to be operated upon.

In operation, the boot or shoe being operated upon is taken, after the lasting operation and while still on the last, and the outer face of the insole brought into engagement with the rapidly rotating corrugated roller 33, the shoe being supported by resting the same on the anvil, it being understood that the last remains in the shoe during the beating operation. The corrugations on the roller 33 strike the stitching or rib a rapid succession of light blows, beating down and smoothing out the inseam to a level with the outer face of the insole, and preparing the

shoe for the subsequent operation of attaching the outsole.

While I have shown and described the preferred embodiment of my invention somewhat in detail, it is to be understood that I may vary the size, shape, and arrangement of parts comprising my invention within wide limits without departing from the spirit of the invention.

Having thus described my invention, what I claim as new, is:—

1. An improved inseam beating and smoothing machine comprising a pair of forwardly extending horns, a corrugated beating and smoothing roller mounted thereon, an adjustable plate, and a conical anvil mounted on said plate and associated with the beating and smoothing roller.

2. An improved inseam beating and smoothing machine comprising a base, a pair of forwardly extending horns mounted thereon, a shaft rotatably mounted in said horns, a beating and smoothing roller on said shaft, an adjustable plate on said base, and a conical anvil mounted on said plate and associated with the beating and smoothing roller.

3. An improved inseam beating and smoothing machine comprising a base, a pair of forwardly extending horns mounted thereon, a shaft rotatably mounted in said horns, driving means therefor, a corrugated beating and smoothing roller mounted on said shaft, an adjustable plate on said base, and a conical anvil mounted on the plate and associated with the beating and smoothing roller.

In testimony whereof, I have signed my name to this specification.

SIDNEY C. WILSON.
